UNITED STATES PATENT OFFICE.

CHARLEY MORTON, OF WARRENSBURG, MISSOURI.

VENTILATOR FOR TOILETS.

1,207,605.

Specification of Letters Patent.

Patented Dec. 5, 1916.

Application filed July 21, 1916. Serial No. 110,593.

To all whom it may concern:

Be it known that I, CHARLEY MORTON, a citizen of the United States, residing at Warrensburg, in the county of Johnson and State of Missouri, have invented new and useful Improvements in Ventilators for Toilets, of which the following is a specification.

This invention relates to ventilators for toilets, and it has for its object to produce a ventilating device adapted to be attached to and used in connection with a toilet seat whereby noxious gases and odors will be carried off, thereby promoting cleanliness and sanitation.

One object of the invention is to produce a ventilating device which when applied to a toilet seat will be capable of being readily connected with a flue located at either side or to the rearward of the seat, such flue leading to the outer air.

A further object of the invention is to produce in connection with the seat and ventilator a packing device which will snugly engage the top edge of the toilet bowl to form a substantially gas proof joint, said joint being broken by an air inlet at the extreme forward end of the seat in order to admit air to produce a draft whereby noxious gases will be carried through the exit.

A further object of the invention is to produce a seat having a packing device as described, said seat and packing device being composed of two parts hingedly connected together to afford access to the bowl for the purpose of cleaning the same, this being necessary because the rearward part of the seat with which the ventilating device is connected is compelled to remain stationary.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited,

but that changes, alterations and modifications within the scope of the claims may be resorted to when desired.

In the drawings,—Figure 1 is a top plan view of a toilet seat provided with the improved ventilator, parts of the latter having been broken away. Fig. 2 is a bottom plan view of the same. Fig. 3 is a side elevation. Fig. 4 is a front view. Fig. 5 is a longitudinal vertical sectional view taken on the line 5—5 in Fig. 1. Fig. 6 is a perspective detail view showing the ventilator detached.

Corresponding parts in the several figures are denoted by like characters of reference.

The improved ventilator consists of a metallic box or casing 15, the same being open at its forward end to produce an inlet 16 of large area, and said box being provided with two rearwardly extending limbs 17, each having a rearwardly extending collar 18 and a laterally extending collar 19, said collars surrounding the outlets of the casing. Tightly fitting caps or closures 20 are provided for such of the collars as are not in present use.

The toilet seat 21 is provided in the rearward portion thereof with a notch or recess 22 between the side walls of which the box or casing 15 is accommodated, said casing being, however, of such dimensions as to extend materially below the seat. The side walls of the casing are provided with laterally extending flanges 23 which are secured by means of screws or other fasteners on the under face of the seat. The seat is provided on the underside thereof with supporting cleats 24 on the under faces of which packing material 25 is secured, said packing material consisting of felt or the like which is readily compressible between the cleats and the top edge of the bowl so as to form a joint that will be practically impervious to gases.

The cleats and packing material are interrupted at the extreme forward end of the seat to produce an inlet 26 for the admission of air which will assist in producing a draft through the outlets of the ventilator, whereby noxious gases will be constantly carried off. The seat 21, as well as the cleats 24 and packing material 25, are bisected transversely, the front and rear parts being connected together by hinges 27 which will permit the front portion of the seat to

2
be raised to afford access to the toilet bowl. A washer 28 of rubber or analogous material is supported between the ventilator and the top edge of the bowl, said washer being connected in any convenient manner with the ventilator.

When the improved device is installed, one of the outlets of the ventilator is connected with an outlet pipe or duct, a portion 10 of which is seen at 29, said duct having been previously installed in a convenient position with relation to the toilet bowl. Inasmuch as such outlet duct is found in different positions, sometimes to the rearward of the 15 bowl and sometimes adjacent to one side or the other, the ventilator is for convenience provided with outlet collars leading not only rearwardly but also laterally to both sides, thus enabling the desired connection 20 to be readily established. For such of the outlet collars as are not in present use the tightly fitting caps or closures 20 are provided.

As will be readily seen from the foregoing 25 description, taken in connection with the drawings hereto annexed, I have provided an extremely simple and effective ventilat-

ing device which is capable of being readily applied and installed.

Having thus described the invention, what 30 is claimed as new, is:—

1. A toilet seat having a recess in the rearward portion thereof, a ventilator casing fitted in said recess and having flanges secured on the under face of the seat, and an 35 outlet duct with which the ventilator casing is connected, said seat being transversely bisected, and hinges whereby the front and rear parts of the seat are connected together. 40

2. A toilet seat having a recess in the rearward portion thereof, a ventilator casing fitted in said recess and having flanges secured on the under face of the seat, an outlet duct with which the ventilator casing is 45 connected, cleats on the underside of the seat, and packing material mounted on said cleats to engage the top edge of a bowl with which the seat is connected, said seat, cleats and packing material being transversely bisected, and hinges whereby the front and rear parts of the seat are connected together. 50

In testimony whereof I affix my signature.
CHARLEY MORTON.
